BERNARD KWARTIN, OF PHILADELPHIA, PENNSYLVANIA

SOUND-REPRODUCING INSTRUMENT

Application filed August 13, 1927. Serial No. 212,646.

This invention relates to sound reproducing instruments, such as talking machines, and more particularly to regulator mechanisms operatively associated therewith for permitting the rendition of compositions of greater length than has been heretofore possible.

As has been pointed out in my copending application, Serial No. 193,871, filed May 24, 1927, to which attention is particularly directed, it is well known that in talking machines of the present known type it is practically impossible to record or reproduce musical compositions of any considerable length due to the fact that records of sufficient size cannot be conveniently made and also to the fact that the talking machines themselves are not designed to accommodate records, the diameters of which are excessive. As a result, it has been the common practice to either abridge or otherwise condense the longer musical compositions, which has always been unsatisfactory to the appreciative lovers of good music, or else to provide a multiple arrangement of records to permit the records to be reproduced in succession, this latter expedient being subject to numerous mechanical and other disadvantages.

In the usual type of modern record, the sound grooves are in the form of a flat spiral decreasing in diameter gradually from the outer periphery thereof to the center, and inasmuch as the speed of the record is constant, the relative speed between the reproducing needle and the grooves of the record in which it travels will be greater near the periphery of the record than at the center, this relative speed being gradually decreased as the needle travels toward the center. Obviously this means that in the vicinity of the center of the record the sound wave impressions which are capable of being converted into sound waves are greater in number for each unit of length, this number for the same unit of length being gradually decreased as the record grooves increase in diameter. This increasing reduction in the number of sound wave impressions per unit of length as the grooves become greater in diameter is responsible for the present practice of providing records which are

only capable of reproducing compositions the time for reproduction of which is relatively short.

In order to obviate the aforementioned objections and difficulties in the way of rendering compositions of greater length than usual there has been shown and described in my prior application above referred to a record disk having on its playing surface the usual sound impression grooves which decrease gradually in diameter from the outer edge of the record to the center thereof but which differ from the usual grooves in that the number of sound wave impressions remain constant for each unit of length of the grooves regardless of their individual diameters.

In my prior application I have also shown and described the provision of a regulating mechanism operatively associated with the motor mechanism for imparting a varying speed of rotation to a record having a constant number of sound wave impressions per unit of length whereby a record of given diameter may be enabled to render compositions of considerably greater length than has been possible heretofore, the record being gradually increased in speed as the reproducing needle approaches the center thereof.

The provision of the improvements in talking machines as shown and described in my above referred to copending application not only makes possible the rendition of a composition of greater length, but it also makes possible the more perfect reproduction of ensemble playing, that is, the reproduction of two or more instruments simultaneously through individual reproducing needles operating upon the same record. With the ordinary record now in use this has not been practicable due to the fact that the use of two or more needles operating upon such a record would obviously result in reducing the playing period of the composition to be rendered. It will accordingly be seen that it is among the objects of the present invention to provide an arrangement whereby records of the type disclosed in my above mentioned copending application may be utilized most effectively in the reproduction of orchestral, band, or other ensemble instrumental or vocal music in a better, clear-

er, and more perfect manner than is now possible.

A further object of the invention is the provision of means whereby a plurality of reproducing units may be used either independently of each other or cojointly in connection with a single reproducing record, the playing grooves of which are characterized by the fact that the number of sound wave impressions per unit of length is constant irrespective of the individual diameters of said grooves. This object is of paramount importance where it is desired to attain more perfect reproduction of ensemble music inasmuch as each individual reproducing unit can be provided with the particular type of diaphragm which is best suitable for reproducing a sound of particular character. For instance, for sounds of high pitch a diaphragm of smaller diameter and less thickness will be found to be more desirable than one of larger diameter and greater thickness, the latter being more suitable for a sound of lower pitch. A single diaphragm designed to reproduce all sounds, whether they be of high or low pitch, is accordingly never satisfactory inasmuch as the best that can be done in such a case is to proportion the diaphragm to sounds of average pitch. Not only does this use of a single diaphragm for reproducing a number of sounds of varying pitches result in sounds, none of which are true in quality, but the fullness or quantity of sound volume is also seriously interfered with, especially where it is desired to reproduce a greater number of instruments or voices of varying pitches. The present invention obviates all of these objectionable features by providing an arrangement of mechanisms which are operable to insure the maintenance at all times of the individuality of each instrument or voice brought together in an ensemble rendition.

A still further object of the present invention is the provision of a pitch adjusting and regulating mechanism which is operatively associated with the speed control mechanism shown and described in my above mentioned copending application, this pitch adjusting and regulating mechanism being so arranged as to provide that pitch or tone quality which is best suited for any particular record. It is, of course, within the contemplation of this invention and the invention disclosed in my prior application to provide records of different diameters, all of which records, however, are characterized in that each is provided with a constant number of sound wave impressions per unit of length of its playing grooves, and further in that the speed of rotation of each record is so controlled that exactly the same interval of time is required for the needle to travel over any given length of a groove regardless of its respective location on the record. By imparting a greater or less

initial speed of rotation to any particular record, its pitch or tone quality will be correspondingly raised or lowered due to the fact that the relative speed between the reproducing needle and the sound wave impressions will have been initially changed, but having once made the necessary pitch adjustment the relative speed between needle and sound wave impressions, and accordingly the pitch, will remain the same throughout the rendition of the entire composition inasmuch as exactly the same interval of time will be always required for the needle to pass over any given number of sound wave impressions. 70 75 75

A still further object of the invention is the provision of a pitch regulating and adjusting mechanism whereby the pitch or tone quality may be suitably adjusted for any record, be it of large or small diameter, this same mechanism being further operable to permit a similar adjustment for pitch when it is desired to employ a record of the usual type, that is, a record which is operated at constant speed and in which the number of sound wave impressions per unit of length is 80 85 90

Due to the fact that the invention disclosed in my earlier application above referred to makes possible the rendition of compositions of considerably greater length than has been heretofore possible without sacrificing any of the quality and the fullness of tone, the playing of ensemble music may be greatly facilitated by providing a record whereon have been individually recorded the tones or notes from different musical instruments or different voices. With the ordinary record this has never been found to be practicable for the reason that its period of reproduction, which is short to begin with, is shortened even more depending upon the number of different instruments or voices which have been individually recorded thereon, it being understood, of course, that these instruments or voices must be reproduced in synchronism by means of several reproducing needles traversing simultaneously the sound wave impressions formed in the record by the different instruments or voices. 95 100 105 110 115 Accordingly, in order to improve the rendition of ensemble selections and at the same time to make possible their reproduction without abridging or otherwise condensing them it becomes a still further object of this invention to provide a single record upon which has been individually recorded two or more instruments or voices of different pitches together with means for effecting their faithful reproduction synchronously or in the particular order necessitated by the selection being rendered. 120 125

Where it is intended to reproduce a single instrument or voice or a combination of instruments or voices having approximately the same pitch or tone quality, it may be nec-

essary to employ only a single reproducing needle. However, where the instruments or voices are of distinctly different pitch, it will be found desirable, for the reasons already stated, to cause them to be individually recorded upon a single record, and it will accordingly become necessary to employ a separate reproducing needle for each of said instruments or voices of different pitch. If, for instance, only two needles are found necessary to satisfactorily reproduce an ensemble selection, such as a duet, it will be obvious that the effective playing surface of the record for each needle, that is, the total length of each of the two different sound wave impression grooves, will be approximately one-half the playing surface of a record necessitating the use of only one needle. Similarly, where four needles are employed, one for each of four different sound wave impression grooves, the effective playing surface of the record as a whole will be reduced to one-quarter of that of a record using only a single needle. Obviously, this reduction in total playing surface of the record, this reduction being dependent upon the number of individual sound wave impression grooves provided in each record, necessitates a corresponding change to be made in the playing time of the record. It is accordingly a further object of this invention to provide a speed changing mechanism which is operatively associated with the speed regulating mechanism described in detail in my earlier application, this speed changing mechanism being operable to cause said speed regulating mechanism to permit the record, when two reproducing needles are to be simultaneously employed, to be gradually increased in speed at a rate which is approximately twice that of the normal rate of increase, and at a rate which is approximately four times the normal rate when four reproducing needles are employed upon the same record.

A still further object of the invention is the provision of a mechanism which is operable not only to increase the rate of increase of rotation of the record as the number of reproducing needles employed is increased, but which is also operable to disconnect the motor mechanism from the speed regulating mechanism whereby to throw the latter out of operation in order to permit the use of the usual record in which the number of sound wave impressions per unit of length is not constant and the speed of rotation of which is not intended to be varied. Other objects, and objects relating to details of construction, economy and efficiency of operation, will appear more fully hereinafter.

The invention consists substantially in the construction, combination, arrangement and relative location of parts, all as will be ex-

plained more fully hereinafter, as illustrated in the drawings showing a preferred form of the invention, and finally pointed out in the appended claims.

In the drawings, which show for purposes of illustration a preferred embodiment of the principles of this invention:

Figure 1 is a top plan view of the apparatus showing the relative arrangement of the speed regulator mechanism, the pitch regulating and adjusting mechanism, and the speed changing mechanism for varying the rate of change in speed or acceleration of the record;

Figure 2 is a vertical cross section view taken on the line 2—2 of Figure 1;

Figure 3 is a horizontal cross section view through the lower guide member as taken on the line 3—3 of Figure 2;

Figure 4 is a vertical cross section view taken on the line 4—4 of Figure 1 showing the speed changing mechanism for varying the rate of change in speed or acceleration of the record;

Figure 5 is a vertical cross section view showing the pitch regulating and adjusting mechanism;

Figure 6 is a view showing the gearing relation between the motor mechanism and the regulator mechanism when only one reproducing needle is employed, the rate of change in speed of the record being then of smallest amount;

Figures 7 and 8 are views similar to Figure 6 but showing the gearing relations between motor and regulator mechanisms which are necessary in order to obtain higher rates of change in speed of the record, as when two or four reproducing needles are used simultaneously upon the same record;

Figure 9 is a view showing the regulator mechanism entirely disconnected from the motor mechanism whereby to permit the use of an ordinary record;

Figure 10 is an enlarged view of the speed regulating mechanism, the initial position of the main lever being shown by the full lines and the more advanced positions thereof by the dotted lines;

Figure 11 is a top plan view of an apparatus embodying the principles of this invention, the figure showing particularly an arrangement for rendering an ensemble selection, the record being provided with a plurality of individual sound impression grooves each of which is arranged to be traversed by a separate reproducing needle;

Figure 12 is a side view of an apparatus also embodying the principles of this invention, the figure showing particularly an arrangement for simultaneously reproducing the sounds from several different instruments or voices, certain of which sounds have been individually recorded upon one record and

the remainder of which have been individually recorded upon a second record; and

Figures 13 and 14 show, respectively, enlarged front and side views of a multiple 5 reproducing unit such as is shown in Figures 11 and 12.

Referring to the drawings, and more particularly to Figures 1 and 2, it will be seen that the invention is primarily based upon 10 the use of a record of the disk type and in which the sound wave impressions per unit of length are constant in number, exactly as in my prior application, Serial No. 193,871. In view of the fact that a record of this particular type has been shown and described 15 in detail in said prior application, a further description of such record is deemed unnecessary and superfluous at this time and will accordingly not be attempted, it being merely sufficient to point out that with such a record characterized by the uniformity of sound wave impressions per unit of length over its 20 entire playing surface it becomes possible to render compositions of considerably greater 25 length than has been possible heretofore.

In order to most effectively utilize such a record having a constant number of sound wave impressions per unit of length, it is necessary to vary the speed of rotation of the 30 record as the reproducing needle travels toward the center thereof so that exactly the same interval of time will be required for the needle to pass over any given length of a playing groove regardless of its distance 35 from the center of the record. A mechanism for so regulating this speed of rotation has been described in said prior application and will be briefly referred to herein in order to render the present invention more readily 40 understood. As in the former instance, it will be seen that there has been provided the usual reproducing apparatus or talking machine 10 above the upper surface of which is rotatably mounted the turn-table 11 for supporting the record to be played. This turn-table 11 is actuated by the usual operating 45 motor 12 suitably geared or otherwise connected to the turn-table shaft 13. This operating motor 12 is mounted in the usual manner in compartment 14 provided below the turn-table 11. Disposed to one side of and arranged to be suitably geared to the motor 12 or to the turn-table shaft 13 in the manner to be explained more fully hereinafter is a 50 screw 15, this screw being rotatably supported in such manner that upon rotation of the turn-table shaft it will in turn be rotated through the said gearing to be presently described. In this particular instance it has 55 been found preferable to mount the screw 15 such that its longitudinal axis lies in a horizontal plane and arranged to cooperate with the screw is the speed regulating lever 16, this lever being pivotally supported, as at 17, 60 such that the ends thereof project in oppo-

site directions from this pivotal point of suspension. It will be observed that in the particular arrangement herein illustrated, the lever 16 oscillates in a substantially horizontal plane and is provided with a laterally extending finger 18 arranged to constantly bear against the outer face of the speed governor disk 19. This latter disk 19 is longitudinally 70 slideable with respect to and forms part of a centrifugal governor 20 which is suitably geared to the shaft 13 of the turn-table 11. It will be apparent that as the lever 16 travels along the screw 15 in the manner and by means of the mechanism described in detail in 75 said copending application, the laterally extending finger 18 will bear with less and less force upon the disk 19 with the result that the speed of rotation of the turn-table will be permitted to increase gradually as the reproducing needle approaches the center of 80 the record. Suitable means are provided, as for instance a spring such as has been described in my copending application aforesaid, for drawing the lever 16 into initial 85 starting position.

As has been already indicated, it is one of the objects of the present invention to provide a mechanism which is operable to regulate and adjust the pitch or tone quality for any given record, this mechanism being operatively associated with the speed regulating mechanism which has been briefly referred to above.

A further object of the invention is to provide a mechanism which makes possible the 100 rendition of ensemble music, this mechanism being also operatively associated with said speed regulating mechanism and being operable to reduce the rate of increase in speed of rotation of the record as the number of 105 reproducing needles employed is increased, this latter mechanism being also operable to disconnect the motor mechanism from the speed regulating mechanism whereby to throw the latter out of operation in order to 110 permit the use of the ordinary record in which the number of sound wave impressions per unit of length is not constant and the speed of rotation of which is not intended 115 to be varied. A preferred arrangement of mechanisms for carrying out these objects will now be described, it being understood, of course, that other arrangements for effecting the same results may be had without departing from the spirit or principles of this 120 invention.

Referring again to Figures 1 and 2, it will be seen that the turn-table shaft 13 is provided with a bevelled gear 21, which is normally in mesh with a similar gear 22 provided at the inner end of a horizontally extending shaft 23. This shaft 23 extends radially from the turn-table shaft 13 and is provided at its outer extremity with a bevelled gear 24, this gear 24 being in mesh with the 125

bevelled gear 25 of the shaft 26 arranged for rotation about a vertical axis. Secured to this vertical shaft 26 at a point above the bevelled gear 25 is a horizontally disposed gear 27.

The screw 15 of the speed regulating mechanism differs somewhat from that shown and described in my prior application in that it is provided with a bevelled gear 28 arranged 10 for meshing engagement with a bevelled gear 29 rotatable about a vertical axis. This last mentioned bevelled gear 29 is supported for rotation upon a vertical shaft 30, which shaft also carries a gear 31 suitably keyed or otherwise secured thereto. This gear 31 underlies the bevelled gear 29 and is arranged for rotation in a horizontal plane above that of the gear 27. For purposes of this description, the gear 27 may be designated the driving gear while the gear 31 may be designated the driven gear. It will be apparent that upon the provision of a suitable means for effecting entrainment between the said driving gear 27 and the said driven gear 31, a 25 connection will be had between the turntable shaft 13 and the screw 15 such as will permit the latter to be operated to control the speed of rotation of the former by means of the mechanism described and claimed in de- 30 tail in said prior application.

In this particular instance, the means for effecting entrainment between these driving and driven gears comprises a multiple gear unit, indicated generally by the reference 35 numeral 32, which unit is operable to vary the speed gear relation between said driving and driven members. As appear most clearly in Figures 2 and 4, the screw 15 of the speed regulating mechanism is provided with 40 a yoke 33 of substantially inverted U-shape, the arms of which embrace opposite sides of the bevelled gear 28, the lower ends of the yoke arms being provided with suitable bearings within which the screw 15 is freely ro- 45 tatable. This yoke is rigidly supported in position by means of an arm 33', preferably formed integrally with the yoke, and is pro- 50 vided with an upwardly presenting laterally offset bearing point or support 34. Extend- 55 ing upwardly from and in axial alignment with this bearing point is the central operating shaft 35 of the multiple gear unit 32. This shaft 35 is provided at its lower end with a socket within which is received the lower 60 bearing point 34, and the upper end thereof projects through an opening 36 provided in the top wall of the compartment 14. A collar 37 secured to the shaft 35 at a point immediately beneath the top wall of the cabi- 65 net prevents the shaft from being raised in an upward direction, it being understood that movement in the opposite direction is pre- 70 vented by reason of the lower end of the shaft 35 being positively seated over the bearing support 34 of the yoke 33.

Extending laterally from the socketed lower end of the shaft 35 is an arm 38, the outer end of which is provided with a vertically extending interiorly threaded sleeve or collar 39. Preferably the arm 38 is formed integrally with the shaft 35, but it may be rigidly secured thereto in any other suitable manner, and this arm 38 extends in a direction and is of a length such that the sleeve 39 at the free end thereof is vertically spaced above a point lying approximately between the opposed peripheral edges of the driving gear 27 and the driven gear 31. A vertically extending stem or rod 40 is threadedly received within the sleeve 39, the upper portion of this stem or rod being extended upwardly through an arcuated slot 41 provided in the top wall of the compartment 14 and the extreme upper end thereof being provided with a knob 42 for the purpose to be presently explained.

Extending laterally from the extreme upper end of the central shaft 35 is a lever 43, this lever lying in substantially the same vertical plane as does the laterally extending arm 38. Secured to the under surface of this lever 43 at a point intermediate the ends thereof is a tubular member or ferrule 44, the latter being in vertical alignment with the sleeve 39 within which the rod or stem 40 is threadedly received. As appears most clearly in Figure 4, this ferrule 44 is provided with a flange 45 underlying the under surface of the top wall of the compartment 14 so as to effectually preclude any tendency for the lever 43 to be lifted vertically away from said top wall. The lever 43 is provided with an extension 46 suitably provided with an operating knob 47, this extension 46 being hinged to the main body of the lever 43, as at 48. A leaf spring 49, one end of which is secured to the main body of the lever and the other and free end of which is in contact with the hinged extension, serves to normally maintain said hinged extension in the position shown in Figure 4. The arcuated slot 41, which has been referred to above, is of a width sufficient to accommodate the ferrule 44 and it will be seen that when the lever 43 is shifted horizontally in one direction or another with the shaft 35 serving as the central axis of rotation, the stem or rod 40 will be correspondingly shifted to one side or another, the extent of said shifting being limited by the length of the arcuated slot 41 in which the ferrule 44 is slidable.

The stem or rod 40 terminates at a point just above the bottom of the compartment 14 and a lower guide for the bottom end of said rod is provided in the form of a hollow member 50, the side walls of which are curved to correspond with the side walls or edges of the arcuated slot 41 in the top wall of the compartment 14. This bottom guide member 50 is preferably secured to the bottom of the 130

compartment in any suitable manner. As appears most clearly in Figures 3 and 4, it will be seen that the stem or rod 40 is threaded only throughout its upper length, the lower length thereof being provided with vertically spaced abutments 51 and 52. A set of gears 53, 54 and 55 is centrally supported between the abutments 51 and 52 by means of a pair of upper and lower coil springs 56 and 57', these gears being rigidly secured one to the other and being arranged for simultaneous rotation about the stem or rod 40. It will be observed that the gears 53, 54 and 55 are of different diameters, the smallest gear being arranged uppermost and the largest gear being arranged lowermost. By virtue of the fact that the stem or rod 40 is threaded into the sleeve 39 of the laterally extending supporting arm 38, it will be seen that the gears 53, 54 and 55 may be adjusted vertically as a unit merely by turning the knob 42 which is fixed to the upper end of the stem 40, these gears being further adapted to be horizontally shifted by the simple expedient of shifting the lever 43 to one side or the other as described above.

Figures 6, 7, 8 and 9 show the several possible relations which may be had between the driving gear 27 and the driven gear 31. 30 Where the record is of the type requiring only a single reproducing needle to faithfully reproduce the selection which is to be rendered, as when only a single instrument or a voice or a number of instruments or voices 35 of the same tone qualities have been recorded upon the same record, the gearing relation between the driving gear 27 and the driven gear 31 is that such as is shown in Figure 6. In this instance it will be seen that the multiple gear unit comprising the gears 53, 54 and 55 has been lowered by means of the adjusting knob 42 and has been properly shifted or oscillated into the necessary position 40 for effecting entrainment between the driving gear 27 and the driven gear 31 through the intervention of the smallest and largest gears of the multiple gear unit, the smallest gear 53 being brought into mesh with the driven gear 31 and the largest gear 55 into mesh 45 with the driving gear 27. The result is that a speed gear ratio between the driving and driven gears is obtained which produces that rate of increase in speed of rotation of the record which is necessary where only the 50 single reproducing needle is employed, this rate being preferably considered as the normal rate of increase in speed of rotation.

In the case of a record requiring the simultaneous use of two needles, as in the case of 60 two instruments or voices, or two sets of instruments or voices of distinctly different pitch characteristics, it becomes necessary to double the acceleration or rate of increase in rotation of the record as the needles simultaneously approach the center thereof. In

order to provide this necessary change in acceleration in speed of the record, the gearing relation between the driving gear 27 and the driven gear 31 becomes that shown in Figure 7 wherein it will be seen that the driving gear 27 is in meshing engagement with the intermediate gear 54 while the driven gear 31 is in like engagement with the smallest gear 53 of the multiple gear unit. As a result of this change in the gearing relation between the driving and driven gears, the latter is driven at an increased speed and the rate of change in speed of the record as the needles travel toward the center thereof is accordingly doubled. This change in the gearing relation to permit the use of two reproducing needles is effected by lowering the stem or rod 40 after the lever 43 has been shifted to one side sufficiently to permit the gear 54 to mesh with the driving gear 27.

In a similar manner when it is desired to play a record for which four needles are required, as when four instruments or voices or four sets of instruments or voices of different pitch characteristics have been recorded on a single record, it becomes necessary to still further increase the acceleration or rate of increase in speed of the record, this being accomplished by shifting the lever still further to one side and by vertically lowering the multiple gear unit until the smallest gear of said unit is brought into meshing engagement with both the driving gear 27 and the driven gear 31, this gearing relation being most clearly shown in Figure 8. The gears 31 and 27 being of the same size, it will be evident that the latter will be driven at the same speed as the former with the result that the turn-table 11, and accordingly the record which is carried thereon, will be accelerated, as the four reproducing needles simultaneously approach the center of the record, at a rate which is four times that of the normal rate.

In order to insure the proper positionment of the multiple gear unit 32 with respect to the driving and driven gears 27 and 31 so that the desired gear ratio may be had between the latter gears when 1, 2 or 4 reproducing needles are employed upon the same record, there is provided to one side of the turn-table 11 a number of vertically extending pins 56, 57 and 58. These pins are arranged upon an arc the center of which is the vertical axis of the central operating shaft 35 of the multiple gear unit 32. The hinged portion 46 of the operating lever 43 for this multiple gear unit is in turn provided with an aperture or opening 59 within which one or the other of these pins 56, 57 and 58 may be received depending upon the particular position of the multiple gear unit. It will be understood that when the particular gearing relation shown in Figure 8 is desired to be had, as when four reproducing needles

are to be employed in connection with a single record, the hinged section of the operating lever 43 is lifted and moved laterally to a position such that the pin 56 may be received 5 within the opening 59 in said hinged section of the lever. With the pin 56 so engaged in the opening 59 (the leaf spring 49 serving to prevent the hinged section from being inadvertently lifted off said pin) the multiple 10 gear unit 32 will have been locked in position against lateral movement.

When it becomes necessary to shift the multiple unit into the position which is necessary when two reproducing needles are to be 15 employed in connection with the same record, the hinged section of the shifting lever 43 is lifted off the pin 56 and is shifted to the right (looking at Figure 1) and into engagement with the pin 57. With the pin 57 in 20 such engagement with the shifting lever 43, the multiple gear unit will be located in the position shown in Figure 7. And in like manner when it is necessary to obtain the lowest rate of increase in speed of rotation of the 25 record, as when only a single reproducing needle is employed, the lever 43 is shifted still farther to the right and into engagement with the pin 58. With the lever 43 engaging the 30 pin 58, the relation between the driving and driven gears will be that shown in Figure 6.

In order to secure the multiple gear unit 32 against vertical displacement during the time that said unit is in one or the other of the 35 positions shown in Figures 6, 7 and 8, the ferrule 44 which is carried by the shifting lever 43, is provided with a set screw 60 which is threaded into engagement with the vertically extending stem or rod 40 upon which the multiple gear unit is rotatably supported. 40 The portion of this stem or rod 40 which extends upwardly above the upper surface of the shifting lever 43, this portion being preferably smooth, may be provided with suitable graduation marks or lines 61, the position 45 of each of which with respect to an index 61' above said upper surface of the shifting lever 43 serves to indicate the vertical position of the multiple gear unit 32, thus facilitating the vertical adjustment of the latter. 50 If desired, the pins 56, 57 and 58 may also be suitably marked to facilitate the lateral adjustment of the multiple gear unit when 1, 2 or 4 needles are to be employed upon a single record.

55 An additional pin 62, which is similar to the pins 56, 57 and 58, may be provided for engagement with the opening 59 in the shifting lever 43, the engagement of this pin 62 with the lever 43 serving to lock the multiple 60 gear unit in a laterally adjusted position which is sufficient to effect disengagement of the multiple gear unit 32 from the driving gear 27. It will thus be seen that provision is had for entirely disengaging the driving 65 gear 27 from the driven gear 31, the relative

positions of these driving gears and the intermediate multiple gear unit being most clearly shown in Figure 9. It thus becomes possible to entirely disconnect the motor mechanism of the apparatus from the speed regulating mechanism so as to render the latter inoperative whenever it becomes desirable to use an ordinary record of the type wherein the number of sound wave impressions per unit of length is not constant and the speed of rotation of which is not intended to be varied. In other words, when the lever 43 is shifted sufficiently to one side to permit engagement therewith by the pin 62, the entire speed regulating mechanism is thrown out of operation and the apparatus may be employed in the ordinary manner for reproducing records of the usual type.

70 The pitch regulating and adjusting mechanism which is operatively associated with the speed regulating mechanism will now be described. Referring particularly to Figures 1, 2 and 5, it will be seen that this pitch regulating and adjusting mechanism is supported in position by means of a bracket 63 secured to the under surface of the top wall of the compartment 14. This bracket 63 is provided with a horizontally extending arm 64 at the outer end of which is supported for rotation a vertically extending shaft 65. This shaft 65 extends upwardly through an opening 66 in said top wall and is provided at its upper extremity with an operating knob 67. The portion of the shaft 65 which extends below the arm 64 of the supporting bracket is provided with a bevelled gear 68 arranged for meshing engagement with a similar gear 69 provided at the extreme outer end of the screw 15. Also supported in the arm 64 of the supporting bracket for rotation about a vertical axis is a short shaft 70, the lower end of which is provided with a relatively large gear 71 arranged for meshing engagement with a relatively small gear 72 secured to the lower end of the shaft 65. Secured to the upper end of the shaft 70 is a relatively small gear 73, this latter gear being arranged for meshing engagement with a relatively large gear 74 coaxially arranged but rotatable with respect to a shaft 65. An index finger 75 overlying the top wall of the compartment 14 is secured to the gear 74 for rotation therewith about the axis of the shaft 65 as its center of rotation. If desired, a graduated pitch regulating scale 76 may be secured to the upper surface of said top wall immediately beneath the plane of rotation of the index finger 75. It will be evident that upon rotation being imparted to the screw 15 through the train of gearing herein before described, the shaft 65, by reason of the meshed gears 68 and 69, will be caused to rotate at a certain definite speed. The index finger 75, however, which is indirectly connected to the shaft 65 through 75 80 85 90 95 100 105 110 115 120 125 130

the train of reduction gearing comprising the gears 71, 72, 73 and 74, will be rotated at a much slower rate, the reduction in speed being such that the index finger will travel from 5 one end of the scale to the other during the time that it takes for the entire record to be played. For convenience, the graduated scale 76 is marked from zero to 100 as is best shown in Figure 1.

10 It is well known that in the reproduction of phonograph records, the pitch is dependent upon the relative speed with which the reproducing needle passes over the sound wave impressions in the record grooves. If this speed 15 is increased, the pitch obtained will be higher than that when the needle passes over these impressions at a slower rate, and it will accordingly be evident that if the initial speed of rotation of a record of the type with which 20 this invention is particularly concerned is increased the pitch will be correspondingly raised, and conversely if this initial speed be decreased the pitch will be correspondingly lowered. This increase or decrease in initial 25 speed of rotation of the record is obtained by means of the pitch regulating and adjusting mechanism just described, it being understood of course that regardless of the initial starting speed of the record the rate of increase in speed of rotation thereof, or in other words its acceleration, remains the same throughout the rendition of the entire composition, the degree of this acceleration being determined by the particular speed gear relation 30 between the driving and driven gears 27 and 31. It is also to be understood that this invention offers no particular restriction as to the diameter of any particular record, it being merely necessary that the threaded portion 35 of the screw 15 over which the speed regulating lever 16 travels be of a length sufficient to permit a record of greatest diameter to be reproduced.

40 When it is desired to play one of the smaller records, say a ten inch record, the pitch regulating knob 67 is manipulated in such manner as to bring the index finger 75 to approximately the point 20 of the scale 76. By so manipulating this pitch regulating knob 67, the screw 15, through the meshed gears 68 and 69, will be rotated sufficiently to cause the speed regulating lever 16 to assume the position shown in Figure 1. The laterally extending finger 18 of this lever will then be exerting a certain braking effort upon the governor disk 19 so that the turn-table 11, and accordingly the record carried thereon, will be caused to rotate at a predetermined 45 initial speed. If one needle is all that is necessary to reproduce the composition which is recorded upon this record, the multiple gear unit 32 is thrown into the position shown in Figure 6, and the record will continue to rotate at a gradually increasing speed of rota- 50

tion until the single reproducing needle approaches the center of the record. It will be understood that if a higher or lower pitch is desired, the pitch regulating knob 67 is rotated in one direction or another to vary the initial starting position of the speed regulating lever 16 upon the screw 15. Preferably the records which are intended to be reproduced in this manner and which are of the type wherein the number of sound wave impressions are uniform over its entire playing surface will have designated thereon in any suitable manner the number of reproducing needles which are to be employed and also that particular pitch setting at which the apparatus should be set to secure the attainment of most satisfactory results.

55 If the record be of larger diameter, say a sixteen inch record, the pitch regulating knob is manipulated in such manner that the index finger 75 is approximately opposite the zero end of the scale, the speed regulating lever then assuming the position shown by the full lines in Figure 10. In this position of the lever 16 with respect to the speed regulating screw 15, a greater traveling length along the screw 15 will be afforded for said speed regulating lever. As in the former instance, the pitch regulating knob 67 may be manipulated slightly in one direction or the other to adjust this lever 16 upon the screw 15 so that the proper initial starting speed will be obtained in order to provide that particular pitch setting which is necessary in order to insure the most satisfactory results from the record to be rendered. In this instance, exactly as in the instance where a smaller size record is to be rendered, the acceleration or the rate of increase in speed of rotation of the record remains the same throughout the entire rendition of the composition and is dependent solely upon the particular speed gear ratio which is had by shifting the multiple gear unit 32 into one or another of the positions shown in Figures 6, 105 and 8.

110 The same pitch adjusting and regulating mechanism which has just been described may be used with the same effect when a record of the usual type and which is arranged to rotate at constant speed is employed. When it is desired to use such a record, it is merely necessary to shift the shifting lever 43 to one side sufficiently to effect disengagement between the driving and driven gears 27 and 31 (see Figure 9) so that the speed regulating mechanism as such is thrown out of operation. It then becomes only necessary to manipulate the pitch regulating and adjusting knob 67 in such manner as to bring the index finger to a point approximately opposite the number ninety of the index scale, the result being that the speed regulating lever 16 is brought into the outermost position shown in Fig. 10. The laterally extend- 120

ing finger 18 of the lever in this position exerts a constant pressure upon the governor disk 19 and acts in all respects exactly like an ordinary pitch regulating device. Obviously, the braking effort which this finger 18 exerts upon the governor disk 19 may be varied within limits merely by turning the pitch regulating and adjusting knob 67 in one direction or another with the result that the 10 desired constant speed of rotation for the record may be obtained.

As has been already indicated the provision of the mechanism for changing the speed gear ratio between the driving gear 27 and 15 the driven gear 31 is of paramount importance in those cases where it is desired to attain more perfect reproduction of ensemble music, as when two or more reproducing needles are used for reproducing synchronously 20 the sounds from several instruments of different pitch characteristics. In Figure 11 there has been shown, more or less diagrammatically, a record of the type with which this invention is particularly concerned, that 25 is, a record having a constant number of sound wave impressions per unit of length of the playing groove. This particular record 77 is provided with four such grooves, designated *a*, *b*, *c* and *d*, each of which is distinct 30 from the other and in each of which are the respective sound wave impressions produced by one of several instruments or sets of instruments of different pitches. For the sake of clearness, the grooves *a* and *b* have been 35 shown by heavier lines than those of the grooves *c* and *d*. Obviously, in order to reproduce the ensemble music which has been recorded upon the record 77, four reproducing units are required, one for each of the 40 individual playing grooves *a*, *b*, *c* and *d*, these units being designated by the reference numerals 78, 79, 80 and 81.

Preferably, these units 78, 79, 80 and 81 are paired as indicated in Figure 11, the units 45 78 and 79 comprising one set and the units 80 and 81 comprising a second set. These sets are of the construction more particularly illustrated in Figures 13 and 14 wherein it will be seen that each unit thereof comprises 50 a sound box 82 including a diaphragm 83 and a reproducing needle 84. The sound boxes of each are complementally shaped with respect to each and are arranged in overlapping relation such that the distance 55 between points of the reproducing needles does not exceed 2 to 3 mm. It is well known that for sounds of high pitch a diaphragm of smaller diameter and less thickness will be found to be more desirable than one of 60 larger diameter and greater thickness, the latter being more suitable for a sound of lower pitch, and accordingly the several reproducing units 78, 79, 80 and 81 may be of different sizes. In the particular arrangement shown in Figure 11, the units 78 and 80

are of smaller size than the units 79 and 81, the units 78 and 80 being adapted for instruments of relatively high tones and the units 79 and 81 being adapted for instruments of relatively low tones.

Connected to each sound box 82 of the several reproducing units is a sound conducting tube 85, the tubes leading from each set of units being pivotally connected at their outer ends, as at 86, to a common duct 87 which is in communication with the sound amplifier box (not shown). In order to permit the needles of each set of reproducing units to move laterally with respect to each other as they travel from the outer periphery of the record toward the center thereof, the tubes 85 are formed of two sections hinged together as at 88. Should it become necessary or desirable to remove one or more of the reproducing units from operative position, it is merely necessary to swing the particular units upwardly and away from the record, this being possible due to the pivotal connection which is had between the conducting tubes 85 and their common duct 87.

Figure 12 illustrates an arrangement for reproducing synchronously two records 89 and 90 upon each of which have been recorded the sounds from four sets of instruments of distinctly different tones, thus making it possible to render an ensemble selection from eight instruments or sets of instruments of different tonal qualities.

Insofar as the number of reproducing units for each record is concerned, the arrangement is substantially similar to that shown in Figure 11. It will be understood, of course, that in the arrangements shown in Figures 11 and 12 the gearing relation between the driving and driven gears 27 and 31 is similar to that shown in Figure 8, this being due to the fact that four needles are being simultaneously employed upon one record with the consequence that it becomes necessary to increase the rate of increase in speed of rotation of the record as the needles approach the center thereof. Any suitable means may be employed for insuring synchronous operation of the two records, it being preferable, as in the particular arrangement shown, to employ a pair of vertically spaced turn-tables 11 both of which are rigidly mounted upon the turn-table shaft 13.

While several different arrangements have been shown and described hereinbefore, it will, of course, be understood that still other arrangements may be devised from time to time for attaining the results desired without departing from the principles or spirit of this invention, and it is intended accordingly 120 to claim the invention broadly, as well as specifically, as indicated in the appended claims.

What is claimed as new and useful is:

1. In a talking machine, in combination, a

- turn-table for supporting a record to be played, a reproducing unit operatively associated with said record, power means for imparting rotation to said turn-table, means operatively associated with said power means and operative independently of said reproducing unit for gradually increasing the speed of rotation of said turn-table, and means operative to change the rate of increase in speed of rotation of said turn-table.
2. In a talking machine, in combination, a turn-table for supporting a record to be played, a reproducing unit operatively associated with said record, power means for rotating said turn-table at substantially constant speed, a regulating mechanism operable solely by said power means and independently of said reproducing unit to gradually vary the speed of rotation of said turn-table from a lesser speed to said constant speed, and means operatively associated with said power means to change the rate of increase in said speed of rotation.
3. In a talking machine, in combination, a turn-table for supporting a record to be played, power means for rotating said turn-table, a governor for controlling the speed of rotation of said turn-table, a regulating mechanism operatively associated with said governor and coacting therewith to gradually vary the speed of rotation of said turn-table, and a variable driving connection interposed between said regulating mechanism and said power means.
4. In a talking machine, in combination, a turn-table for supporting a record to be played, power means for rotating said turn-table, a regulating mechanism operable upon said turn-table to gradually vary the speed of rotation thereof, and a multiple gear unit interposed between said regulating mechanism and said power means.
5. In a talking machine, in combination, a turn-table for supporting a record to be played, power means for imparting rotation to said turn-table, a regulating mechanism operable upon said turn-table to gradually vary the speed of rotation thereof, said mechanism including a rotatable screw and a lever arranged for actuation by said screw, and means for changing the speed gear relation between said screw and said turn-table whereby to vary the speed of rotation of said screw and accordingly the speed of operation of said lever.
6. In a talking machine, in combination, a turn-table for supporting a record to be played, power means for imparting rotation to said turn-table, a screw driven by said power means, a pivotally supported lever, one arm of which is arranged to travel on said screw and the other of which operates as a brake to control the speed of rotation of said turn-table, and means interposed between said screw and said power means and arranged to effect a change in the speed of rotation of said screw.
7. In a talking machine, in combination, a mechanism including a regulating screw for regulating the speed of rotation of a record to be played, said mechanism being operable solely by the operation of said screw to effect a gradual increase in speed of rotation of said record as the composition played upon said record approaches its end, and means for varying the rate of increase in speed of rotation of said record.
8. In a talking machine, in combination, power means for imparting a definite speed of rotation to a record to be played, a screw arranged for rotation about its longitudinal axis, a lever pivotally supported for oscillation in the plane of said longitudinal axis, one branch of said lever being arranged to travel along said screw and the other arm thereof being operable as a brake to control the speed of rotation of said record, and a multiple gear unit interposed between said screw and said power means, said unit being arranged for vertical and lateral adjustment to effect entrainment between said screw and said power means through one or the other of the gears of said unit.
9. In a talking machine, in combination, power means for imparting a definite speed of rotation to said turn-table, a screw operatively associated with said power means for rotation thereby, a brake lever normally in threaded engagement with said screw for permitting the speed of rotation of said record to be gradually increased from a lesser speed to said definite speed as said lever travels upon said screw, a multiple gear unit including a plurality of concentrically arranged gears of different diameters interposed between said power means and said screw, one of said gears being constantly entrained with said screw, and means for causing any one of said gears to be entrained with said power means whereby to vary the speed gear ratio between said screw and said power means.
10. In a talking machine, in combination, a turn-table, a disk record supported upon said turn-table for rotation therewith, said record being characterized in that the playing surface thereof is provided with a plurality of independent spiral grooves, a reproducing needle arranged to travel in each of said playing grooves, power means for rotating said turn-table and record at a definite speed, a regulator mechanism operable by said power means to permit the speed of rotation of said record to be increased to said definite speed as a maximum as said reproducing needles simultaneously travel toward the center thereof, and means for changing the rate of increase in said speed of rotation depending

upon the number of said independent playing grooves provided upon said record.

11. In a talking machine, in combination, a turn-table, a disk record supported upon said turn-table for rotation therewith, power means for rotating said turn-table and said record, a screw operatively associated with and arranged to be driven by said power means at any one of a number of different speeds, a pivotally supported lever arranged to travel along said screw upon rotation of the latter, said lever operating as a brake to control the speed of rotation of said turn-table, and means operative to rotate said screw independently of said power means whereby to initially position said lever at any desired point along said screw.

12. In a talking machine, in combination, a turn-table for supporting a disk record the sound wave impressions of which are constant in number per unit of length of the playing grooves, a reproducing needle arranged to travel in said playing groove, a regulator mechanism operable independently of the movement of said needle to control the speed of rotation of said record such that the same interval of time is required for said reproducing needle to pass over any given number of said sound wave impressions, and means operatively associated with said regulator mechanism for varying the time required for the needle to pass over said given number of sound wave impressions.

13. In a talking machine, in combination, a turn-table for supporting a disk record provided with sound impression grooves in the form of a flat spiral wherein the number of sound wave impressions are constant per unit of length of the grooves, power means for imparting rotation to said turn-table, a speed regulating mechanism operable exclusively by said power means to permit the speed of rotation of said record to be increased gradually from a predetermined initial starting speed, and means operable upon said speed regulating mechanism for adjusting the same to permit the rendition of a composition of greater or shorter length.

14. In a talking machine, in combination, a turn-table for supporting a record to be played, said record being provided with a definite number of separate sound impression tracks on the playing surface thereof wherein the number of sound wave impressions are constant per unit of length, a reproducing needle arranged to travel in each of said tracks, a speed regulating mechanism arranged to permit the speed of rotation of said turn-table to be gradually increased from a predetermined starting speed as said reproducing needles travel simultaneously toward the center of the record, and means operatively associated with said speed regulating mechanism for changing the rate of increase in speed of rotation of said turn-table

when a record is employed having a greater or lesser number of sound impression tracks.

In testimony whereof, I have hereunto affixed my signature.
